Primary Examiner — April Rivas*Assistant Examiner* — Tia Ruth-Renee Polidori**CLAIM**

The ornamental design for a shaker bottle, as shown and described.

DESCRIPTION

FIG. 1 is a top, front and right side perspective view of a shaker bottle, showing my new design in an exploded configuration for clarity of disclosure;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof, showing my new design in an assembled configuration of use;

FIG. 8 is a bottom plan view thereof;

FIG. 9 is a top, front and right side perspective view thereof; and,

FIG. 10 is an enlarged view of portion 10 in FIG. 9.

The evenly dashed broken lines illustrate features of the shaker bottle that form no part of the claimed design. The unevenly dashed broken lines define the boundary of enlarged views and form no part of the claimed design.
